UNITED STATES PATENT OFFICE.

ANNA M. GELWICKS, OF DECATUR, ILLINOIS.

INFLATABLE DRESS-FORM.

SPECIFICATION forming part of Letters Patent No. 399,322, dated March 12, 1889.

Application filed January 19, 1889. Serial No. 296,897. (No model.)

To all whom it may concern:

Be it known that I, ANNA M. GELWICKS, of the city of Decatur, county of Macon, and State of Illinois, have invented a certain Improved Form for Dress-Makers, of which the following is a specification.

It is the object of my invention to provide a form over which garments may be fitted, and which may be readily varied in size and modified to some extent in proportion. I attain my object by means of the device hereinafter set forth and claimed.

In the drawing accompanying and forming a part of this specification, *a* represents in dotted lines a bust formed of thin uniformly-elastic material impervious to air. The openings of the neck, hip portion, and sleeves are closed by blocks or plates *b c* and *h h*, respectively. An internal structure to lengthen or shorten the bust and arms, or either, comprises rods *d f f*, attached to closure *b*, rod *d'*, attached to closure *c*, rods *f' f'*, attached to closures *h h*, brace-rods *m m*, extending from rod *d* to rods *f f*, and turn-buckles *e g g*. Rods *d d'* and turn-buckle *e* connect closures *b* and *c* and regulate the length of the bust. Rods *f f'* and turn-buckles *g* connect the sleeve-closures with the neck-closure and regulate the length of the sleeves. Braces *m m* hold rods *f* in position and prevent the adjustment of the sleeves from affecting the form of the bust. The turn-buckles *e g g* are right and left threaded, and the ends of the rods conform to this construction. Valve *i* opens into the form through closure *c*, and the pipe or

tube *k* enables air to be forced into the form by means of a bellows or other suitable contrivance.

While the form is empty the structure is shortened or lengthened to conform to the required length measures, and the form is afterward inflated more or less to conform to the required circumferential measurement. The form being originally perfect and the material uniformly elastic, it will be seen that its tendency is to expand or contract without changing the proportions, except as affected by the adjustment of the internal structure. This enables a garment to be fitted accurately and easily, and insures a more perfect shape than could ordinarily be got by the more inconvenient way of fitting the garment to the wearer.

I claim as new and desire to secure by Letters Patent—

The inflatable form *a* of uniformly-elastic material, the closures *b c h h*, the rods *d d'*, secured to the closures *b* and *c*, respectively, and reversely threaded at their ends, the reversely-threaded turn-buckle *e*, rods *f f'*, connected with closures *b* and *h h*, respectively, and reversely threaded at their ends, the reversely-threaded turn-buckles *g g*, braces *m m*, air-admitting tube *k*, and valve *i*, all in combination, as set forth.

ANNA M. GELWICKS.
